UNITED STATES PATENT OFFICE

146,413

DESIGN FOR A CLOCK OR SIMILAR ARTICLE

Martin H. Lencer, Los Angeles, Calif.

Application July 16, 1946, Serial No. 131,627

Term of patent 3½ years

(Cl. D42—7)

To all whom it may concern:

Be it known that I, Martin H. Lencer, a citizen of the United States, residing in Los Angeles, in the county of Los Angeles, State of California, have invented a new, original, and ornamental Design for a Clock or Similar Article, of which the following is a specification, reference being had to the accompanying drawing, forming a part thereof.

Figure 1 is a front perspective view of a clock showing my new design, the essential features of which are shown in full lines; and

Figure 2 is a front elevational view of the same.

The rear of the clock, not shown, is plain.

I claim:

The ornamental design for a clock or similar article, substantially as shown and described.

MARTIN H. LENCER.
